T. B. HUBBARD

ROD BENDER

Filed May 24, 1924

Inventor

Theo B Hubbard

By

Hardway Tait, Attorneys

UNITED STATES PATENT OFFICE.

THEO BOYD HUBBARD, OF HOUSTON, TEXAS.

ROD BENDER.

Application filed May 24, 1924. Serial No. 715,761.

To all whom it may concern:

Be it known that I, THEO BOYD HUBBARD, a citizen of the United States, residing at Houston, in the county of Harris and State 5 of Texas, have invented certain new and useful Improvements in a Rod Bender, of which the following is a specification.

This invention relates to new and useful improvements in a rod bender.

10 One object of the invention is to provide a device of the character described specially designed for the purpose of bending rods, such as reinforcing rods for concrete and the like.

15 Another object of the invention is to provide an implement of the character described which is of very simple structure and may be cheaply produced and easily handled.

With the above and other objects in 20 view, this invention has particular relation to certain novel features of construction, operation and arrangement of parts, an example of which is given in this specification and illustrated in the accompanying 25 drawings, wherein:-

Figure 1 shows a plan view of the device.

Figure 2 shows a side elevation.

Figure 3 shows a plan view showing a 30 filler block employed in bending small rods; and,

Figure 4 shows a cross sectional view taken on the line 4—4 of Figure 1.

Referring now more particularly to the 35 drawings, the numeral 1 designates the base block, preferably of wood, whereon is mounted a metallic plate 2, which may be bolted thereto, and which is formed with an upturned flange 3. Spaced from one end

of the flange 3, there is a hole 4, through the plate 2, and base 3, forming a bearing. 40

The numeral 5 designates a handle, one end of which is overturned forming a spindle 6, which is adapted to work in said bearing, and spaced from said spindle there is a depending lug 7, formed integrally with 45 the handle.

In use the rod to be bent is placed on the plate 2, alongside the flange 3 and the spindle 6 is inserted in the bearing 4 with the handle extending transversely with respect 50 to the rod, so that the rod will be in the notch between the spindle and lug 7. The handle may then be swung around the required distance to give the desired bend or angle. 55

In case small rods are to be bent a filler block, as 8, may be employed, and interposed between the flange 3 and the rod. This block may have a U-shaped extension 9, if desired to receive the end of the flange 60 3, which will hold the block in upright position.

What I claim is:

In combination a rod bender comprising a base formed with a socket bearing therein; 65 a portion of said base being integral and upturned forming a flange spaced from the bearing, a filler block associated with the flange, a handle formed at one end with a spindle adapted to work in said bearing and 70 a depending lug carried by the handle lying in the same plane as said spindle and spaced therefrom.

In testimony whereof I have signed my name to this specification.

THEO BOYD HUBBARD.
